BROOM BRIDLE

Otto R. Grube, Egg Harbor City, N. J.

Application December 20, 1948, Serial No. 66,277

1 Claim. (Cl. 15—170)

1

This invention relates to broom bridles designed for use in clamping broom straws together, at a point between the sweeping end of the broom and the wires used in securing the broom straws to the handle.

An important object of the invention is to provide a device of this character which may be readily and easily applied to the usual broom head, the bridle being adjustable for use in connection with broom heads of various thicknesses.

Still another object of the invention is to provide means for attaching the broom bridle to the broom head in such a way that it will not become displaced while the broom is being used in sweeping.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawing

Figure 1 is an elevational view of a broom head supplied with a broom bridle, constructed in accordance with the invention.

Fig. 2 is an elevational view of the opposite side of the broom head, showing the invention as applied.

Fig. 3 is a perspective view of the broom bridle the elements thereof being disconnected prior to positioning on a broom head.

Referring to the drawing in detail, the reference character 5 indicates a broom head of the usual and well known construction, the broom head including the broom straw securing wires 6.

The bridle forming the subject matter of the present invention, comprises bars 7 constructed of substantially wide material, the bars being of lengths to extend across substantially the entire width of the broom head with which it is used.

These bars 7 when positioned, are disposed in parallel relation with respect to each other at opposite sides of the broom head, as clearly shown by Fig. 1 of the drawing, the bars being formed with openings disposed in spaced relation with the ends thereof, which openings accommodate the bolts 8 that extend through the straws of the head, and pass beyond the outer surface of the cooperating bar, where it is supplied with a washer 9 and nut 10.

Connecting the bars 7 at their ends, are end pieces 11, which end pieces are constructed of

2

suitable flexible material such as leather, the end pieces being curved around the edges of the broom head as shown by Figs. 1 and 2 of the drawing. The end pieces 11 are formed with openings that align with the openings of the bars 7 so that the bolts 8 will pass through the end pieces and secure the end pieces in place at the ends of the bars 7. Thus it will be seen that when the bars are positioned and the end pieces have been secured in place, the straws of the broom head will be firmly clamped and held braced eliminating uneven wear of the brushing end of the head caused by sweeping.

The reference character 12 indicates securing arms which are formed with eyes 13 at one of their respective ends, which eyes also accommodate the bolts 8 securing the arms 12 to the bridle.

These arms 12 are formed with right angled 20 end portions 14 that terminate in end portions 15 that are disposed at right angles to the portions 14, the portions 15 being flattened and sharpened so that they may be readily driven into the head of the broom, between straws, and 25 when the securing arms are properly twisted to align the eyes 13 with the openings of the bars 7 to receive the bolts 8, the end portions 15 will lie in parallel relation with the opposite outer surface of the broom head, holding the bridle against movement longitudinally of the broom head. It 30 might be further stated that when positioning these securing arms 12, they are positioned between adjacent wires 6 so that they will engage one of the wires which provides a permanent 35 stop for the arms to prevent the arms from movement.

From the foregoing it will be seen that due to the construction shown and described, I have provided a broom bridle embodying bars which 40 clamp the outer surfaces of the head of the broom, the flexible end pieces 11, permitting of slight movement of the bars while the broom is used in sweeping, thereby reducing wear to a minimum.

Having thus described the invention, what is 45 claimed is:

In a broom bridle, a pair of parallel bars adapted to be fitted against opposite outer surfaces of a broom head, flexible end pieces adapted to be 50 fitted around the side edges of the broom head, bolts extending through aligned openings in the bars and the flexible end pieces securing the bars and end pieces together, said bolts also being adapted to pass through the broom head, securing the bars and flexible end pieces together, se-

curing arms having eyes through which the bolts extend holding said securing arms in position between said bars, the free ends of said securing arms being extended at right angles with respect to the main portions of the arms, the extremities of the right-angled portions extending at right angles to the first-mentioned right-angled portions and adapted to be extended between broom straws of the head of the broom, securing the bridle against movement longitudinally of the 10 broom head.

OTTO R. GRUBE.
